US0D1064946S

(12) **United States Design Patent** (10) **Patent No.:** **US D1,064,946 S**
(45) **Date of Patent:** **** Mar. 4, 2025**

(54) **FRONT BUMPER FOR MOTOR VEHICLE**

(71) Applicant: **Dr. Ing. h.c. F. Porsche**
Aktiengesellschaft, Stuttgart (DE)

(72) Inventor: **Emiel Burki**, Stuttgart (DE)

(73) Assignee: **Dr. Ing. h.c. F. Porsche**
Aktiengesellschaft (DE)

(**) Term: **15 Years**

(21) Appl. No.: **29/893,514**

(22) Filed: **May 31, 2023**

(30) **Foreign Application Priority Data**

Feb. 21, 2023 (EM) 015011986-0006

(51) **LOC (15) Cl.** **12-16**

(52) **U.S. Cl.**

(57) **CLAIM**

The ornamental design for a front bumper for motor vehicle as shown and described.

DESCRIPTION

FIG. 1 is a front-left side perspective view of a front bumper for motor vehicle embodying my new design;

FIG. 2 is a front elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The broken lines in the drawings illustrate portions of the front bumper for motor vehicle that form no part of the claimed design.

1 Claim, 6 Drawing Sheets
